(57) **CLAIM**

We claim the ornamental design for a current transformer body, as shown and described.

DESCRIPTION

FIG. 1 is a side elevation view of a current transformer body showing our new design, in an open condition;

FIG. 2 is an opposite side elevation view thereof;

FIG. 3 is a right side elevation view thereof;

FIG. 4 is a left side elevation view thereof;

FIG. 5 is a top plan view thereof;

FIG. 6 is a bottom plan view thereof;

FIG. 7 is an elevated perspective view thereof;

FIG. 8 is a side elevation view thereof, in a closed position;

FIG. 9 is an opposite side elevation view thereof;

FIG. 10 is a right side elevation view thereof;

FIG. 11 is a left side elevation view thereof;

FIG. 12 is a top plan view thereof;

FIG. 13 is a bottom plan view thereof; and,

FIG. 14 is an elevated perspective view thereof.

The broken lines in the various views are for illustrative purposes only, and form no part of the claimed design.
